UNITED STATES PATENT OFFICE

2,387,161

DOOR LIFTING MECHANISM

Thorvald Madland, Chicago, Ill., assignor to The Youngstown Steel Door Company, Cleveland, Ohio, a corporation of Ohio

Application March 13, 1943, Serial No. 479,065

3 Claims. (Cl. 16—99)

This invention relates to door lifting mechanisms and is directed primarily to lift mechanisms for sliding railway house car doors.

It is an object of this invention to materially reduce the cost of door lifting mechanisms by the elimination or substantial reduction of castings, machining operations, and the reduction of the number of different parts required to be stocked by the railroads.

It is a further object of this invention to provide door lifting mechanisms as characterized above which shall be applicable to all railway house cars and operable by movement of a lever in either direction in a plane parallel to the doors.

A further object is to provide door lifting mechanisms, as described above, which shall require less force to lift the doors than is required by lifting mechanisms now utilized.

Other objects of the invention will become clear as the description thereof proceeds.

In the drawings forming part of this specification:

Fig. 1 is a fragmentary elevation of a sliding door for railway house cars to which a lift mechanism embodying the instant invention is applied.

Fig. 2 is a vertical section taken on line 2—2 of Fig. 1.

Fig. 3 is a horizontal section taken on line 3—3 of Fig. 1.

Fig. 4 is a vertical section taken on line 4—4 of Fig. 1.

Fig. 5 is a horizontal section taken on line 5—5 of Fig. 1.

Fig. 6 is a horizontal section taken on line 6—6 of Fig. 1.

The instant invention is embodied in a lift mechanism shown applied to a sliding door 10 for railway house cars. The door 10 comprises a metallic panel 11 formed with a plurality of horizontal corrugations 12 which merge at their ends into upwardly and outwardly offset portions 13 and 14. The metallic panel 11 at each vertical margin thereof terminates in flanges 15 and 16 which are parallel to the main plane of the panel. The front vertical margin of the panel is reinforced by means of a backing plate 17 riveted thereto and by means of a reinforcing member 18 secured to the flange 15 and to the backing plate 17, as more clearly shown in Fig. 1 of the drawings. The rear vertical margin of the panel is reinforced by means of a backing plate 19 fastened thereto and by means of a reinforcing member 20 secured to the flange 16 of the panel

and to the backing plate, as more clearly shown in Fig. 1 of the drawings.

The structure of the door 10, as described hereinabove, is shown in greater detail in the patent to Ditchfield 1,895,151 to which reference is made.

At its lower portion the panel 11 is flanged outwardly, as indicated at 21, and then downwardly to provide a flange 22 which, as more clearly shown in Fig. 2 of the drawings, is offset outwardly relative to the main plane of the door. A backing plate 23 extending substantially the full width of the door is secured to the panel in the main plane thereof above flange 21, as by means of rivets 24.

The backing plate 23 and the structure of the door panel described immediately above provide space for the application of the lift fixture embodying the instant invention. The lift fixture comprises a Z-shaped member 25 disposed so that the web 26 is horizontal. The flange 27 extends upwardly therefrom substantially in the plane of the panel flange 22 and the flange 28 extends downwardly therefrom substantially in the plane of the backing plate 23. When applied to the door the flange 27 is secured, as by means of rivets, to the panel flange 22 and the flange 28 is secured, as by means of rivets, to the backing plate 23 so as to constitute in association with these members a box section.

The upstanding flange 27 of the Z-shaped member 25 carries spaced bearing members 29 and 30. The bearing member 29, which is preferably formed from a plate, is provided with a flange 31 secured to the upstanding flange 27, as by means of rivets 32 and 33. The bearing member 29 is flanged inwardly, as indicated at 34, and terminates in a flange 35 which lies substantially in the plane of the backing plate 23. The upstanding flange 27 of the Z-shaped member 25 and flange 35 of the bearing member 29 are formed with aligned openings 36 and 37 which function as bearings for the ends of a pin 38 that journals a roller housing 39, as hereinafter explained.

Bearing member 30 is similar in construction to bearing member 29. Bearing member 30 is provided with a flange 40 secured to the upstanding flange 27, as by means of rivets 41 and 42. Bearing member 30 is flanged inwardly, as indicated at 43, and terminates in a flange 44 lying substantially in the plane of the backing plate 23. Aligned openings are formed in the upstanding flange 27 and flange 44 of the bearing member 30, these openings serving as bearings for

the ends of a pin 45 which journals a roller housing 46, as hereinafter explained.

Roller housing 39 is substantially channel shaped in section and embodies a web 47 and spaced inner and outer walls 48 and 49. The web 47, as more clearly shown in Figs. 1 and 3 of the drawings, terminates below the top of the walls 48 and 49. Above the web the walls 48 and 49 are displaced toward each other for a reason which will hereinafter appear. The housing member 39 carries a roller 50 which is mounted upon a pin 51 supported in the walls 48 and 49 of the housing. The pin 38, which journals the roller housing 39 in the upstanding flange 27 and flange 35 of the bearing member extends through the walls 48 and 49 of the roller housing beyond the periphery of the roller 50 and, by reason of the instant invention, may be formed of a length of cold rolled steel.

The roller housing 46 is similar in construction to the roller housing 39 so that the detailed description of the latter will suffice for the former. The pin 45, which journals roller housing 46 in the upstanding flange 27 and flange 44 of the bearing member 40, is similar to the pin 38. Roller housing 46 carries a roller 52 which is mounted upon the pin 53 carried by the walls of the roller housing.

Bearing plates 54 and 55 are carried by the Z-shaped member 25 intermediate the roller housings. These bearing plates, which are preferably located on the vertical center line of the door, are secured to the upstanding flange 27, as by means of rivets 56. Bearing plate 54 embodies an attaching flange 57, an inwardly and upwardly offset flange 58 and an upwardly extending flange 59 which preferably abuts an inwardly offset portion 60 of the outwardly offset flange 22 of the door panel. Bearing plate 55 is formed to provide an attaching flange 61, an inwardly offset flange 62 and an upwardly extending flange 63 which is spaced inwardly sufficiently to permit journalling of an actuating member 64 in aligned openings 65 and 66 formed, respectively, in the bearing plates 54 and 55.

The actuating member 64, which is best illustrated in Fig. 6 of the drawings, comprises a body portion 67 formed with oppositely extending outer and inner trunnions 68 and 69 which are journalled in the openings 65 and 66 of the bearing plates 54 and 55. The actuating member 64 is formed with pairs of oppositely extending ears 70-70 and 71-71 to which connecting bars are adapted to be pivotally fastened, as hereinafter described. The outer trunnion 68 of the actuating member 64 extends through the inwardly offset portion 60 of panel flange 22 so that a lever 72 can be mounted upon the trunnion 68 for the purpose of imparting movement to the actuating member. As more particularly shown in Fig. 4 of the drawings, the lower portion of the lever is disposed within the space provided by the inwardly offset portion 60 so that the projection of the lever beyond the outer plane of the door is reduced. The lever 72 is guided and retained upon the door by means of a plate member 73 fastened to the inner face of the lever and the depending flange 74 of a substantially Z-shaped quadrant 75 fastened to the outer face of the panel 11.

The lever 72, as more clearly shown in Fig. 1 of the drawings, is disposed vertically so that lifting force may be applied to the door upon movement of the lever in its plane in either direction. This movement of the lever is translated

into a lifting force upon the door by means of connecting bars 76 and 77. The bar 76 is disposed between and pivotally fastened to the pair of ears 70-70, as by means of a pin 78. The connecting bar 76 slopes upwardly from its securement to the actuating member and is disposed between the walls of the roller housing 39. Securement of the connecting bar to these walls is obtained by means of a pin 79.

10 The connecting bar 77 similarly has one end disposed between the pair of ears 71-71 to which it is pivotally fastened, as by means of a pin 80. The connecting bar 77 slopes upwardly similarly to the connecting bar 76 from its securement to the actuating member to the roller housing 46 and is pivotally fastened to the walls of the latter roller housing, as by means of a pin 81.

It will be apparent from this construction that the operating lever may be moved in either direction and that in such movement a pull will always be exerted upon the connecting bars 76 and 77. This pull is transmitted to the roller housings 39 and 46 which, accordingly, fulcrum about the rollers 50 and 52 and impart a lifting force to the door through the pins 38 and 42. Uniformity of application of the lifting force to the door is provided by insuring that the centers of the pins which fasten the connecting bars to the ears of the actuating member and to the roller housings lie on the same line as the center of the trunnions 68 and 69. The lifting mechanism hereinabove described lends itself to construction as a unit and application as such to a door. By reason of the fact that the bearing members 30 and 31 are secured to the upstanding flange 27 of the Z-shaped member 25, and by reason of the further fact that the roller housings are carried by the pins 38 and 45 which are supported in the bearing members and in the upstanding flange 27, it is apparent that the bearing members and roller housings can be assembled with the Z-shaped member 25 prior to its application to the door. Similarly, by reason of the hereinabove described construction the bearing plates 54 and 55, the actuating member 64 and the connecting bars 76 and 77 can be assembled with the upstanding flange 27 of the Z-shaped member 25 prior to the securement of the Z-shaped member to the door. Accuracy of assembly of the lifting mechanism and expeditious application thereof to the door are thereby insured.

The lifting mechanism is applied to the door by securement, as by means of rivets, of the upstanding flange 27 to the outwardly offset flange 22 at the door. The backing plate 23 is then riveted to the panel by means of the rivets 24 and to the depending flange 28 of the Z-shaped member 25, as more clearly shown in Fig. 2 of the drawings. The operating lever is then mounted upon the outer trunnions 68 of the actuating member and related to the quadrant 75 in the manner shown in Fig. 4 of the drawings. This assembly completes the box section at the bottom edge of the door and makes the web 26 of the Z-shaped member 25 available as a frictional supporting means for the door when it is in its lowered position. In this position the web 26 frictionally engages a flange 82 of a substantially channel-shaped track 83. This track is supported by means of a plurality of track brackets 84 secured to the lower flange 85 of the track and to a member 86 which serves to reinforce the side sill 87 of the car.

It will be apparent from the foregoing description of the instant invention that the enu-

merated objects thereof are achieved by the illustrated structure. Expensive castings are replaced by simple and inexpensive pressings. Cold rolled steel pins are made available for use as trunnions for the roller housings in place of cast housings heretofore deemed necessary. This fact introduces a further economy in that it eliminates the machining operation required where cast trunnions are employed. Additional savings through the elimination of machining operations are effected by the utilization of pressed plate members for the roller housings. Cast roller housings used at the present time require that bosses be formed on them wherever openings are provided and these bosses must in each instance be machined to provide smooth surfaces. The structure of the operating mechanism and its association with the roller housings not only insure uniform lift of the door but actually permit a reduction in the force required to lift the door despite the fact that the pins which journal the roller housings to the door are disposed at a greater distance from the center of the rollers than in the present lift mechanisms. Moreover, the described mechanism permits a substantial reduction in the distance between lift mechanisms on opposite sides of a car so that it can be applied to doors of all railway house cars irrespective of the width of such cars. This fact permits a reduction in the number of parts of different mechanisms which the railroads must keep in stock.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. Lifting mechanism for a sliding door embodying a panel comprising spaced roller housings, a roller carried by each of said roller housings, a pin carried by and extending through each of said roller housings beyond the periphery of said rollers, said pins being oppositely disposed relative to said rollers, the ends of said pin being adapted to be journalled in said door, said roller housings, rollers and pins lying inwardly of said panel, an actuating member adapted to be journalled in said door inwardly of said panel between said roller housings for rotation in either direction, said actuating

member having horizontally extending ears, a vertical lever mounted on said actuating member on the outside of said door, bars disposed inwardly of said panel and pivotally connected to said ears and said roller housings above said rollers, said lever being operable to rotate said actuating member in either direction to exert a pull only upon said bars and a lifting force upon said door.

2. Lifting mechanism for a sliding door embodying a panel comprising spaced pressed channel-shaped roller housings, a roller carried by each of said roller housings, a pin carried by and extending through each of said roller housings beyond the periphery of said rollers, said pins being oppositely disposed relative to said rollers, the ends of said pin being adapted to be journalled in said door, said roller housings, rollers and pins lying inwardly of said panel, an actuating member adapted to be journalled in said door inwardly of said panel between said roller housings for rotation in either direction, said actuating member having horizontally extending ears a vertical lever mounted on said actuating member on the outside of said door, bars disposed inwardly of said panel and pivotally connected to said ears and said roller housings above said rollers, said lever being operable to rotate said actuating member in either direction to exert a pull only upon said bars and a lifting force upon said door.

3. Lifting mechanism for a sliding door embodying a panel comprising a pressed channel-shaped roller housing, a roller carried by said roller housing, a pin carried by and extending through said roller housing beyond the periphery of said roller, the ends of said pin being adapted to be journalled in said door, said roller housing, roller and pin lying inwardly of said panel, an actuating member adapted to be journalled in said door inwardly of said panel for rotation in either direction, said actuating member having a horizontally extending ear, a vertical lever mounted on said actuating member on the outside of said door, a connecting bar disposed inwardly of said panel and pivotally secured to said ear and said roller housing above said roller, said lever being operable to rotate said actuating member in either direction to exert a pull only upon said connecting bar and a lifting force upon said door.

THORVALD MADLAND.
